UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLL FOR ROLLING-MILLS.

1,259,969.

Specification of Letters Patent. Patented Mar. 19, 1918.

Application filed November 27, 1914. Serial No. 874,126.

To all whom it may concern:

Be it known that I, VICTOR E. EDWARDS, a citizen of the United States, residing at Worcester, in the county of Worcester and 5 Commonwealth of Massachusetts, have invented a new and useful Improvement in Rolls for Rolling-Mills, of which the following, taken in connection with the accompanying drawings, is a specification.

10 The present invention relates to the construction of rolls and roll housings for rolling mills and the like, and has particular reference to the formation of the necks, or bearing portions of such rolls, and the manner of disposing the same within their supporting bearings carried by the roll housings.

An object of the invention is to provide a 20 construction adapted to offer an increased area of bearing for the end thrust of the rolls, over any construction previously used; a further object is to attain greater space for the introduction of lubricant to the bearing surfaces of said rolls, and a still further 25 object is to decrease the cylindrical area of such bearing surfaces to a minimum without affecting the strength and rigidity of the roll supporting means, thereby decreasing the friction produced in the operation of the 30 rolls.

In the accompanying drawings,

Figure 1 is an end elevation of a structure embodying my invention.

Fig. 2 is a side elevation of the same, one 35 of the housings for the rolls being shown in section on the line 2—2, Fig. 1.

Fig. 3 is an enlarged view of one end of 40 a roll, illustrating, diagrammatically, the manner of arriving at the proper proportions for the neck of the same, in accordance with the present invention.

Similar reference characters refer to similar parts in the different figures.

Practice has demonstrated that the severe 45 demands of service, especially in rolling wide thin flats, require, at the innermost points of support for each roll, a neck diameter closely approaching the actual working diameter of the roll, by reason of the 50 strain, namely combined torsional and bending, to which the roll, between its supporting surfaces, is subjected. As a consequence, the

shoulder afforded by the difference in the diameters of the roll and its neck, to resist the end thrust of the roll, is a relatively 55 small one, and furthermore, its effectiveness, as the surface of the roll wears, and is turned down to compensate for such wear, is correspondingly diminished. In addition, the opposing surfaces of the roll bearing-section and the roll, which constitute the above described thrust bearing, are subject at all times to the action of water and scale, rendering the satisfactory lubrication of 60 said end thrust bearing practically impossible. The present invention contemplates an amelioration of the disadvantages above set forth, by the use of rolls having necks of a 65 special and particular formation, as fully set forth hereinafter.

Referring to Figs. 1 and 2, I have illustrated a stand of rolls which, in its general characteristics, is of an approved and regularly adopted construction, the same comprising a pair of housings 1 and 2 adapted to support between them a pair of rolls 3 and 4. Each housing is in the form substantially of a rectangular frame, having upright sides 5, connected by a base 6 and a top or crown 7. The supporting means 75 for the lower roll 3 contemplates a bearing section 8 having lateral ears or flanges 9, 9 which embrace the sides 5, 5 of the housing, to prevent axial displacement of the said bearing section, and also serve to guide said bearing section in its vertical movement by the usual adjusting wedge 10, interposed between the same and the base 6 of the housing. A right and left hand screw 11 provides for the simultaneous movement of the two wedges 10 to raise or lower said bearing sections and with them the roll 3. The supporting means for the upper roll 4 is found 80 in a bearing section 12 provided in each housing and resting normally, at the lowest disposition of said roll, upon shoulders 13, 13 extending inwardly from the sides 5, 5. An upper bearing block 14 for the roll 4 is also carried by each housing, the same having guide ears or flanges 15, 15, embracing the sides 5, 5 in the same manner as do the ears 9 of the bearing blocks 8 for the lower roll 3. Bolts 16 passing through the ears 9 and 15 of the blocks 8 and 14 respectively,

coöperate with the sides 5, 5 of the housings to retain said blocks in any given vertical position of adjustment. Screws 17 carried by the crown 7 of each housing are capable of turning therein to provide an adjustable abutment for the upper bearing blocks 14 of the roll 4, whereby the upward deflection of said roll, due to the passage of the work between the rolls, is limited and controlled. Each roll 3, 4 presents a shoulder 18 in opposition to the inner ends of its bearing sections 8 and 14 respectively, the extent of said shoulder being determined by the difference between the radius of the roll proper, and the required radius of the roll neck or bearing portion, at this point.

The determination of a minimum neck diameter for this point resolves itself into the calculation of a cross-sectional area sufficient to furnish the desired resistance to the combined bending and torsional strains, as previously set forth.

In Fig. 3 I have shown one end of a roll of a given diameter having a neck of predetermined length, the broken line at the left terminating length, the broken line at the left hand end of said figure passing through the longitudinal center of the roll. In said figure, A—A represents the line of equal bending strength for the roll and neck, indicating at any given transverse section, the diameter required to resist bending strains.

The uniform section indicated by the line B—B on said figure represents the diameter required to resist the torsion strains incident to the rotation of the roll by the application of power through the neck, in the usual manner. The line C—C, Fig. 3, represents the section of uniform strength at all points to resist bending and torsional strains combined. The usual practice heretofore has been to compromise strength, in order to get adequate end collars for the roll, the roll neck being turned to a uniform diameter outwardly from the shoulder 18, as indicated approximately by the broken line D—D, Fig. 3, the concave surfaces of the several bearing sections 8, 12 and 14 being correspondingly turned to accommodate roll necks having continuous cylindrical bearing surfaces. However, as seen in Fig. 3, the line C—C, representing at successive axial points, the resultants of the corresponding diameters indicated by the lines A—A and B—B, assumes a gradually convergent direction from the shoulder 18 toward the outer end of the roll neck, and the present invention aims to utilize this characteristic in overcoming the previously mentioned disadvantages common to rolls having their necks formed in accordance with present practices.

It is proposed to obtain additional strength over that afforded in present practice, by increasing the diameter of the neck in the vicinity of the shoulder 18, nearest

the roll proper, and at the same time to obtain more end collar by reducing the portion of the neck which is remote from the roll. In carrying my invention into effect, the section of the roll neck at the shoulder 18 is made to correspond approximately to the section at this point indicated by the line C—C, Fig. 3, the diameter of the same, represented by the dimension $—ab—$, being greater than the diameter given to a roll neck constructed according to existing practices. The roll neck portion thus formed, having the diameter $—ab—$, is extended some distance outwardly from the shoulder 18, and it is terminated at a point in the given length of the neck, where there is offered a sufficient difference between the diameter $—al—$, and the diameter indicated by the line C—C, for the formation of a second shoulder 19, the portion of the neck beyond such point being finished uniformly to the diameter thus indicated by said line C—C at such point.

In carrying out the invention, the bearing blocks 8, 12 and 14 are similarly shouldered, affording reduced sections 20 beyond said shoulders for receiving the reduced ends of the roll necks. In this manner a thrust surface, in addition to that afforded by the ends of the bearing blocks in opposition to the shoulders 18, is formed, and it will be seen that the efficiency of the same is not disturbed by any wear upon the surface of the rolls, and furthermore, this collar is more easily protected from scale and water and hence is better lubricated. In addition, the introduction of the heavy grease used as a lubricant for the roll necks is rendered easier, by reason of the increase in the height of the space 21 between the block 12 and the neck of roll 3, due to the reduction in the size of said neck. The bearing surfaces of the necks being materially decreased, and the lubrication of the same being more perfectly maintained than in rolls of the usual construction, it follows that less power is required to drive said rolls than heretofore. There is less breakage of rolls and less necessity for renewals of bearings, both of which are now serious items of expense in operating mills.

I claim,

1. In a rolling mill, a roll having a neck affording a journal for its rotative movement, said neck being constituted by a portion adjacent the roll of smaller diameter than said roll, and by another portion of smaller diameter than said first portion, the two portions approximating in cylindrical form the minimum section, the uniform strength of which would resist torsional and bending strains on said roll.

2. A roll for rolling mills having a neck portion constituted by cylindrical sections of successively decreasing diameters out-

wardly of said roll, the outermost section having a smaller diameter than that required for a neck of uniform diameter, which would resist the torsional and bending strains on said roll.

3. In a rolling mill, a roll having a neck affording a journal for its rotative movement, said neck being constituted by a portion adjacent the roll of smaller diameter than the roll, whereby to form a shoulder, and a second portion of smaller diameter than said first portion, whereby to form a shoulder between said first and second portions, the two shoulders affording a greater area to resist end thrust than would be afforded by a neck of the required uniform diameter to resist the torsional and bending strains on said roll.

4. In a rolling mill, a roll having a neck affording a journal for its rotative movement, said neck being constituted by cylindrical portions of successively decreasing diameters outwardly from said roll, whereby to approximate in cylindrical form the minimum section of uniform strength which

is adapted to resist combined torsional and bending strains.

5. A roll for rolling mills having a neck portion constituted by cylindrical sections of successively decreasing diameters outwardly of said roll, the innermost section having a larger diameter than that required for a neck of uniform diameter which would resist the torsional and bending strains on said roll.

6. A roll for rolling mills having a neck portion constituted by cylindrical sections of successively decreasing diameters outwardly of said roll, the outermost section having a smaller, and the innermost section a larger diameter, than that required for a neck of uniform diameter which would resist the torsional and bending strains on said roll.

Dated this twenty-first day of November 1914.

VICTOR E. EDWARDS.
